US00D485146S

(12) **United States Design Patent** (10) Patent No.: **US D485,146 S**
Rivera (45) Date of Patent: ** Jan. 13, 2004

(54) **FRONT PORTION OF A PAIR OF JAWS FOR A FOLDING ELECTRICIAN'S TOOL**

Folding Scissors, at least as early Oct. 1994.

(75) Inventor: **Benjamin C. Rivera**, West Linn, OR (US)

(List continued on next page.)

(73) Assignee: **Leatherman Tool Group, Inc.**, Portland, OR (US)

Primary Examiner—Clare E. Heflin
(74) Attorney, Agent, or Firm—Chernoff, Vilhauer, McClung & Stenzel, LLP

(**) Term: **14 Years**

CLAIM

(21) Appl. No.: **29/175,222**

The ornamental design for a front portion of a pair of jaws for folding electrician's tool, as shown and described.

(22) Filed: **Jan. 30, 2003**

DESCRIPTION

Related U.S. Application Data

FIG. 1 is an isometric view from the upper right front of a pair of jaws for a folding electrician's tool, showing my new design, wherein the broken-line depiction of the rearward parts of the jaws is included merely for illustrative purposes and forms no part of the claimed design;

(63) Continuation-in-part of application No. 29/155,106, filed on Jan. 30, 2002, now Pat. No. Des. 474,085.

FIG. 2 is a right side elevational view thereof, wherein the broken-line depiction of the rearward parts of the jaws is included merely for illustrative purposes and forms no part of the claimed design;

(51) **LOC (7) Cl. 08-05**

FIG. 3 is a top plan view thereof, wherein the broken-line depiction of the rearward parts of the jaws is included merely for illustrative purposes and forms no part of the claimed design;

(52) **U.S. Cl. D8/52; D8/105**

FIG. 4 is a bottom plan view thereof, wherein the broken-line depiction of the rearward parts of the jaws is included merely for illustrative purposes and forms no part of the claimed design;

(58) **Field of Search D8/52-56, 58,**

FIG. 5 is a rear, or tang, end elevational view thereof in broken line, included merely for illustrative purposes, and forming no part of the claimed design;

D8/105, 98, 99, 107; 81/305, 380-409,
414-420, 424.5, 427.5, 9.4, 9.44; 7/102,
107, 125-129, 132, 166, 168, 131, 134;
30/34, 143, 153, 155, 161, 90.1, 90.2

FIG. 6 is a front, or blade end elevational view thereof, wherein the broken-line depiction of the rearward parts of the jaws is included merely for illustrative purposes and forms no part of the claimed design; and,

(56) **References Cited**

FIG. 7 is a left side elevational view thereof, wherein the broken-line depiction of the rearward parts of the jaws is included merely for illustrative purposes and forms no part of the claimed design.
